[57] CLAIM

The ornamental design for front panel for a rack mounted rectifier, as shown and described.

DESCRIPTION

FIG. 1 is a front, perspective view of the front panel for a rack mounted rectifier;

FIG. 2 is a top view of the front panel for a rack mounted rectifier;

FIG. 3 is a bottom view of the front panel for a rack mounted rectifier;

FIG. 4 is a left side view of the front panel for a rack mounted rectifier;

FIG. 5 is a rear view of the front panel for a rack mounted rectifier; and,

FIG. 6 is a right side view of the front panel for a rack mounted rectifier.

The broken line showing in FIG. 1 is included for the purpose of illustrating environmental structure only and forms no part of the claimed design.
